UNITED STATES PATENT OFFICE.

SAMUEL BORCHARDT, OF NEW YORK, N. Y.

DESIGN FOR A LEGGIN.

SPECIFICATION forming part of Design No. 21,827, dated August 30, 1892.

Application filed June 16, 1892. Serial No. 436,988. Term of patent 7 years.

To all whom it may concern:

Be it known that I, SAMUEL BORCHARDT, a citizen of the United States, residing in New York city, in the county and State of New York, have invented and produced a new and original Design for a Leggin, of which the following is a specification, reference being had to the accompanying drawings, forming part thereof.

10 Figure 1 is a side elevation of the leggin shown in my design, and Fig. 2 is also a side elevation taken from the opposite side.

Similar figures of reference indicate corresponding parts in both views.

15 The two views are deemed necessary to fully illustrate the design.

The leading feature of the design is the leggin-body, the extension-top, which projects upward from the body portion of the leggin, 20 and the ornamentation separating the extension-top from the body portion of the leggin.

10 is the body of the leggin, and 11 the top. The top edge of the body is scalloped, as shown at 12, and made to overlap the extension-top 11, and beneath the scallop is a 25 row of open panels 13, and the material of which the top is made shows through the panels. On one side of the extension-top are the straps and buckles 14.

The leggin is made with the body and top 30 of contrasting colors, as this heightens the effect of the design and causes the top to show to advantage through the open panels 13.

I claim—

The design for a leggin, herein shown and 35 described.

SAML. BORCHARDT.
